UNITED STATES PATENT OFFICE.

SAMUEL W. JACKSON, OF CHICAGO, ILLINOIS.

VENTILATOR.

1,233,362.

Specification of Letters Patent. Patented July 17, 1917.

Application filed July 29, 1912. Serial No. 712,033.

To all whom it may concern:

Be it known that I, SAMUEL W. JACKSON, a citizen of the United States, residing at Chicago, in the county of Cook and State of Illinois, have invented certain new and useful Improvements in Ventilators, of which the following is a description.

My invention relates to means for use in window or other openings in a building for permitting a substantially uninterrupted circulation of air when desired but excluding rain, insects, dust or other undesirable material.

The object of my invention is to provide a simple, reliable and easily operated device of the kind described, preferably arranged for adjusting its size to suit openings of various widths, and also provided with means for controlling the circulation of air through the device.

To this end my invention consists in the novel construction, arrangement and combination of parts herein shown and described, and more particularly pointed out in the claims.

In the accompanying drawings wherein like or similar reference characters indicate like or corresponding parts:

Figure 1 is a vertical section taken substantially on line 1—1 of Fig. 2.

Fig. 2 is an elevation of one end of my device.

Fig. 3 is an enlarged section of my device taken substantially on line 3—3 of Fig. 2.

Fig. 4 is a section taken substantially on line 4—4 of Fig. 1.

Fig. 5 is a section taken substantially on line 5—5 of Fig. 1.

Fig. 6 is a section taken substantially on line 6—6 of Fig. 7 showing a slightly modified form of my device.

Fig. 7 is a front elevation of the form of my device shown in Fig. 6.

Fig. 8 is an enlarged sectional detail taken substantially on line 8—8 of Fig. 6.

Fig. 9 is a section taken substantially on line 9—9 of Fig. 8.

Fig. 10 is a fragmentary section taken substantially on line 10—10 of Fig. 6.

Fig. 11 is a section taken substantially on line 11—11 of Fig. 12 showing a slightly modified form of my device.

Fig. 12 is a section taken substantially on line 12—12 of Fig. 11.

In the form shown in the drawings, my device consists of a pair of suitably formed side members 1 provided with any desired number of slats 2—2 extending between them at substantially right angles to each. The several slats are preferably attached to the respective side members at two points 3 and 4 so arranged that the lateral inclination of the slat may be adjusted as desired.

In the preferred construction the inner faces of the side members are substantially flat and parallel to each other and a plurality of transverse slots or grooves 5 are provided in each to receive the connections 3 at one edge of the respective slats. A slide 6 is fitted in a longitudinal groove near the opposite edge of the side member 1 adapted to move longitudinally therein and to receive each of the connections 4 at one end of the slats so that by moving the slides 6 longitudinally of the side members, the lateral inclination of the several slats will be adjusted simultaneously as desired, at the same time retaining the transverse location of one edge of all of the slats, that is, the edge of each slat attached to the side 6 will move vertically only, while the opposite edge will adjust itself laterally in the groove 5.

In the preferred construction the slats 7 and 8 at the ends of the side members 2 are slightly wider than the remainder of the slats which are preferably arranged substantially in line vertically and are so arranged upon the side members 1 that one edge of each projects slightly beyond the line of the remaining slats. The slat 7 projects sufficiently to engage the window sash and form a suitable closure therewith adjacent the slide 6 as at 9. In the form shown each slide 6 is provided with a part 10 extending toward the sash and arranged to receive the bearing 4' of this slat. The slat 8 projects at the opposite edge of the device or adjacent the slots 5, and in the preferred construction the bearings 3' for this slat are bent upward slightly to remove the slot 5' slightly farther from the end of the side member 1 as it is desirable to have the extreme edge of the slat 8 substantially in line with the extreme end of the side

member 1 so that when in position in the window the edge of the slat 8 will be in contact with the window sill 11 and form a closure at this point.

5 When thus constructed it is obvious that by adjusting the slides 6 any desired inclination of the slats may be secured. A handle 12 or other convenient means is provided upon each slide 6 for this purpose, 10 and a bolt 14 or suitable means is rigidly secured to the side member 1 and extends through a suitable slot 15 in the slide 6 for rigidly securing the slide in position.

In the preferred form also a spring roller 15 or other convenient means 16 extends between the slides 6 and a bar or roller 17 is mounted in close proximity to the edge 4 to the slat 8. A pair of suitable hooks 18 are provided at the under side of the 20 slat 7 so positioned that when a suitable netting is wound upon the roller with a part extending downward to the bar 17 thence upward between the bar and the edge of the slat 8 and thence to the hooks 18 the 25 netting which is provided with a suitable rod or bar at its free end will be substantially in contact with the edges of the several slats and will operate to exclude insects, leaves and other light, small objects 30 which might be carried in the air between the slats. The slats may be formed in any suitable manner. As shown in Fig. 3 a portion 19 of the slat is bent over at both edges as at 20-20 and a part 21 is positioned 35 between the parts 19 and 20 and arranged to slide longitudinally therein so that the length of the slats may be adjusted within certain limits as desired.

Any suitable means may be provided to 40 rigidly connect the parts 19 and 21 of each slat to hold them in their adjusted position. In the form shown a longitudinal slot 22 is provided in the part 21 and a bolt 23 is rigidly attached to the part 19 and extends 45 through the slot 22 with a wing-nut 24 or other suitable means to clamp the parts together. Suitable means are also provided to secure my device in position. In the form shown screws or bolts 25-25 extend through 50 the side members 1 into the window frame for this purpose.

In the form shown in Figs. 6 and 7 the several parts are constructed substantially the same as hereinbefore described, except 55 that the slots 5 and slides 6 are omitted leaving the faces of the side members smooth. The end of each slat is bent at substantially right angles and a pair of screws or other suitable means 27 extends 60 through the bent up portion 26 of each slat into the side member 28, thereby rigidly securing the several slats in position. In the form also the roller 29 upon which the netting is wound is mounted directly upon

and between the side members 28, and below the upper edge of the lower slat 30 in such a position that when the netting is drawn up and the free end which is of course preferably provided with a suitable rod is attached to the hook 31 upon the upper slat 32, the netting will be deflected outward slightly by the upper edge of the lower slat 30 and will lie substantially in contact with the edges of the intermediate slats. The several slats are arranged in 75 substantially the same general position as hereinbefore described, so as to permit free movement of the window. The slats in this form are arranged to telescope as hereinbefore described, to allow for variation in 80 the widths of the window. In the form shown in Figs. 11 and 12 a suitably formed socket 35 is provided adapted to be attached to the side members by suitable screws 36-36 at its extremities. A suitable bar 85 formed of wood, fiber, or other convenient material extends between the side members with the ends of the bar extending into properly fitting sockets.

Having thus described my improvement 90 it is obvious that various immaterial modifications may be made in my device without departing from the spirit of my invention, hence I do not wish to be understood as limiting myself to the exact form or construction shown.

What I claim as new and desire to secure by Letters Patent is:

1. In a device of the kind described, a frame, comprising a pair of side members and a plurality of slats connecting said side members and positioned at substantially right angles thereto, the slats adjacent the ends of said side members projecting laterally at opposite sides respectively of the remaining of said slats, and means for securing said frame in position, whereby said end slats coöperate with the sash and sill respectively of the window to form a weather proof covering for the window opening.

2. In a device of the kind described, a frame, comprising a pair of substantially parallel side members and a plurality of laterally inclined pivotally mounted slats each engaged at each side member at two points at the extreme edges of said slats, one of which is adapted to move longitudinally only of said side members and the other transversely thereof and positioned at substantially right angles thereto, and means 115 for securing said frame in position.

3. In a device of the kind described, a frame, comprising a pair of side members and a plurality of laterally inclined slats each pivotally engaged at each side member at two points and positioned at substantially right angles thereto.

4. In a device of the kind described, a

frame, comprising a pair of side members and a plurality of slats each pivotally engaged at each side member at two points at the extreme edges of the slats, one of which is adjustable only transversely of said side member and the other only longitudinally thereof.

In testimony whereof, I, have hereunto signed my name in the presence of two subscribing witnesses.

SAMUEL W. JACKSON.
